UNITED STATES PATENT OFFICE.

WILLIAM J. BURKE, OF PORTSMOUTH, OHIO.

SHOE-DRYING LAST.

1,057,801.

Specification of Letters Patent.

Patented Apr. 1, 1913.

Application filed September 20, 1909. Serial No. 518,576.

To all whom it may concern:

Be it known that I, WILLIAM J. BURKE, a citizen of the United States, and a resident of Portsmouth, in the State of Ohio, 5 have invented certain new and useful Improvements in Shoe-Drying Lasts, of which the following is a specification, reference being had to the accompanying drawings, forming a part hereof.

10 In the manufacture of box toes for boots and shoes, present methods ordinarily require three or four days to dry and thoroughly unite the several plies constituting the stiff toe piece, the usual method being 15 to apply a suitable material such as a solution of gums, to the several thicknesses or plies which are to form the toe, then last- 20 ing the same and, when the plies have been well pulled down around the wood of the last, they are allowed to remain upon the last for about twenty-four hours until the 25 shape or contour of the toe is imparted thereto; thereafter the last is removed and the partially formed shoe is again permitted to 30 dry for a couple of days or so. For unless the drying is thoroughly effected at this stage, the subsequent stitching and other machine operations will contract the toe and distort it. Such a method, besides consuming a considerable amount of time, involves the use of a large number of lasts, and requires a considerable floor space.

One of the objects of the present invention is to reduce the time which has heretofore been found necessary in drying and setting box toes and thereby to obviate the other disadvantages in the manufacture of boots and shoes which resulted as a natural consequence from the old methods.

40 Broadly considered, the present invention relates to a last for drying the boot or shoe, and particularly the toe thereof, from within and preferably said last is provided with electric heating means embedded therein. The use of a last containing such means which is readily attachable to and detachable from an electric main, offers a particularly practical and convenient method of constructing box toes and one which does 45 not involve any change in the other operations or machinery required in the manufacture of boots and shoes as the same is practised today.

50 Referring now to the drawings, Figure 1 is a sectional view of a portion of a last in which the improvements have been em-

bodied, the irregular plane of section being indicated by the line 1—1 in Fig. 2. In this figure the several plies forming the toe of a shoe are illustrated in position upon the 60 last, and, Fig. 2 is a view of the same in vertical section, the electrical attaching means being also shown.

The last *a* is shown in the drawings in a conventional form, the rear portion of the 65 last being omitted for convenience in illustrating. In the present case, an electric heater consisting of a suitable coil of fine wire *b*, cylindrical in form, is embedded within the toe of the last in any suitable 70 manner. Surrounding the end of the heater *b* is a metallic piece *c*, preferably in the form of a disk, which has the effect of uniformly distributing the heat to all parts of the toe; and for the purpose of conducting 75 the heat from the interior outwardly, openings *d* are provided in the last and are arranged to radiate substantially from the disk *c* to the exterior of the toe.

The heater *b* may be connected in any 80 suitable manner with an electric main, but it is preferable to provide detachable connections between the heater and the main in order that the device may be the more conveniently handled. For this purpose the 85 heater *b* is connected with a jack *e*, located in the top of the last, by means of wires *f* lying in a recess *g* which is bored in the last and connects the jack with the space in which the heater lies. The electric main, 90 on the other hand, is provided with a plurality of short connectors *h* having plugs *i* adapted to be inserted in the jacks. In this way, as will be obvious, the heater *b* may be readily connected with and disconnected from the main without interfering 95 at all with the normal use of the last. In fact, lasts provided with electric heaters as hereinbefore described, may be used in the same way as ordinary lasts. Where, however, they are used as a quick means of drying the box toes, in accordance with the present invention, the materials of the toe are applied in the ordinary manner and when the shoe is advanced far enough for 100 the drying process to be proceeded with, it is placed in a suitable rack or other receptacle where electrical attachment can be made with the heater. In accordance with the improvements, the toes can be thoroughly dried and the materials thereof 105 united within half an hour, which obviously

2

is a great saving over present methods. Moreover, the improved method of drying from within out has the advantage of setting the leather first in shape and leaving the enameled leather tips (where such leather tips are employed) soft so that they may be stretched to place conveniently and without cracking. Again, the heating of the toes tends to produce a water-proof box toe, and enables the use of materials in forming the toe which it would otherwise be impossible to employ.

The improvements herein set forth are not limited to the precise construction and arrangements shown and described, as they

may be embodied in various forms and modifications without departing from the spirit and scope of the invention.

I claim as my invention:

A last for boots and shoes having a heater supported in the toe, a metallic disk around the heater, and openings in the last radiating from the disk. 20

This specification signed and witnessed this 15th day of September, A. D., 1909.

WILLIAM J. BURKE.
